UNITED STATES PATENT OFFICE

105,135

DESIGN FOR A HAND TRUCK

Harry Palage, Woburn, Mass.

Application April 14, 1937, Serial No. 68,747

Term of patent 14 years

To all whom it may concern:

Be it known that I, Harry Palage, a citizen of the United States, residing at Woburn, in the county of Middlesex, State of Massachusetts, have invented a new, original, and ornamental Design for a Hand Truck, of which the following is a specification, reference being had to the accompanying drawing, forming part thereof.

The figure is a perspective view of my hand truck embodying my new design.

I claim:

The ornamental design for a hand truck, as shown.

HARRY PALAGE.
